INNER CUFF

Louis F. Robert, Au Sable Forks, N. Y.

Application June 30, 1930. Serial No. 464,920

1 Claim. (Cl. 2—124)

This invention relates to removable cuffs and, among other objects, aims to provide an improved auxiliary or inner cuff adapted to be applied to the inside of a negligee shirt, wrist band or attached soft cuff to give a finished appearance to the shirt and to protect the wrist band against wearing and soiling.

In the drawing showing a preferred embodiment of the invention:

10 Fig. 1 is a perspective view showing the improved inner cuff applied to a square-cornered wrist band, the band and cuff being closed and fastened;

15 Fig. 2 is a side elevation showing a slightly different form of inner cuff applied to a round cornered wrist band, the cuff being closed and fastened;

20 Fig. 3 is an elevation showing the type of inner cuff and wrist band shown in Fig. 1, but showing the wrist band open;

25 Fig. 4 is a view similar to Fig. 3, but showing a round cornered wrist band and cuff;

Fig. 5 is a transverse sectional view taken through a wrist band and cuff like that shown in Fig. 3;

30 Fig. 6 is a transverse sectional view taken through a wrist band and cuff like that shown in Fig. 4; and

Fig. 7 is an enlarged sectional view taken 35 through the inner cuff only on the line 7—7 of Fig. 3.

It is a well known fact that soft permanently attached wrist bands on negligee shirts become soiled very quickly by perspiration and dirt as 40 they come in contact with the wrist and hands and present an untidy appearance. The dirt becomes ground into the bands especially along the edges, so that the band must be subjected to harsh treatment when being laundered. Consequently, the band is usually the first part of 45 the shirt to wear out or frazzle and the shirt must then be discarded. The present invention, therefore, provides improved, readily removable inner cuffs whereby to protect split wrist bands against such soiling and to give the wrists a dressy appearance like a collar gives a proper finish and dress to the neck.

Referring particularly to the drawing, the two 50 forms of auxiliary cuffs are there shown applied to permanent wrist bands. Figs. 1, 3 and 5 show a split wrist band or cuff of the horseshoe type wherein the ends are fastened by links or the like; while Figs. 2, 4 and 6 represent the lap-over type of wrist band, wherein the ends are 55 held together by a button and buttonhole. In

both instances, the auxiliary cuff is made and attached to the wrist band in the same general way. In Figs. 1, 3, 5 and 7, the auxiliary or inner cuff 10 is shown as being rectangular in shape to be applied to a wrist band or permanent cuff 11 of the same general shape. The cuff 10 is preferably made of multiply fabric in one piece and thickness such as that used in the so-called "soft collar", and may be hemmed in the same general way. However, in Fig. 7, the edges of the 60 fabric are turned over and held down by means of tape 12 stitched to the fabric. The hem may be of any conventional form, the idea being merely to stiffen the edges of the cuff and to present a 65 finished appearance.

The length of the cuff is slightly less than the 70 wrist band, so that when the wrist band is bent around the wrist with the cuff on the inner side, the end edges of the cuff and band will be aligned. The cuff is also wider than the wrist band as 75 clearly shown, so that when it is properly secured in place, the lower edge 13 extends below the lower edge of the wrist band. Near the top and intermediate the ends of the cuff, a button-hole 14 is provided to co-act with a button 15 80 which may be sewed on the inner side of the wrist band. Instead of buttons and buttonholes, conventional snap fasteners may be used. Near each end of the cuff is a buttonhole 16 adapted to 85 align with the usual buttonholes 17 already provided in the wrist band. Cuff links 18 are adapted to be inserted through the holes 16 and 17 (see Fig. 5) to hold the ends of both the wrist band and cuff together. While the links 18, here 90 shown, are of the snap-fastener type, it is obvious that any kind of links may be used.

In Figs. 2, 4 and 6, the cuff 10a is made the same as cuff 10 with the exception that the ends of the cuff are rounded to conform to the round 95 corners on the wrist band 11a. A similar button-hole 14a and a button 15a are provided and the lower edge 13a of the cuff extends below the wrist band 11a. Similar buttonholes 16a are also 100 formed in the cuff, but in this case, the hole 16a at one end of the cuff is adapted to co-act with a button 19 secured on the inside of the wrist band. The other end of the cuff is between the lapped-over ends of the wrist band; the usual 105 button 20 on the outside of the wrist band extending through the other hole 16a and through the usual buttonhole 21 on the wrist band. If desired, the buttons 19 and 20 may be sewed on the band 11a in the same operation or, instead of buttons, a buttonhole may be provided at 110

that point and a stud inserted through the holes in the band and cuff.

In both forms, it will be seen that the cuffs may be easily and quickly applied or detached and as the lower edges extend below the wrist bands, a very neat and dressy appearance is imparted to the wrist of the wearer. Moreover, the wrist band is prevented from contacting with the wrist, so that it does not become soiled and will not absorb perspiration. Instead, when the cuff is soiled, it may be removed and laundered. The cuffs may be made in various sizes and in either contrasting colors or to match the predominating color of the shirt. Furthermore, as the cuffs are made of a single thickness of multiply fabric, which requires no starching, they will keep the wrists cool and comfortable and permit free movement of the same, without sticking to the wrists, wilting or wrinkling. Also, as the cuff protects the wrist band, the shirts may be made of the most delicate fabrics and the cuffs will hold the wrist bands in shape.

Obviously, the present invention is not restricted to the particular embodiment thereof herein shown and described.

What is claimed is:

In combination with a permanent, split shirt cuff, an inner dress cuff comprising a plain flat strip of multiply, semi-soft fabric of a single thickness shaped to correspond approximately to the shape of the permanent cuff at its lower end and being shorter than the permanent cuff so that its ends will not be exposed beyond the ends of the permanent cuff when fastened; and means removably to secure the inner cuff to the inside of the permanent cuff with the lower edge of the inner cuff projecting a short distance beyond the dress edge of the permanent cuff to provide a contrasting dress edge which protects the edge of the permanent cuff.
